UNITED STATES PATENT OFFICE.

VINCENT J. CONCES, SR., AND VINCENT J. CONCES, JR., OF EAST CHICAGO, INDIANA.

CAR-WHEEL.

1,215,252.

Specification of Letters Patent.

Patented Feb. 6, 1917.

Application filed September 15, 1916. Serial No. 120,413.

To all whom it may concern:

Be it known that we, VINCENT J. CONCES, Sr., and VINCENT J. CONCES, Jr., citizens of the United States, residing at East Chicago, 5 in the county of Lake and State of Indiana, have invented new and useful Improvements in Car-Wheels, of which the following is a specification.

This invention relates to improvements 10 in car wheels and has particular application to a wheel which is purposedly designed for movably supporting cars used in foundries for moving molds, flasks, plates or the like.

15 In foundry use after the mold has been made, it is placed in the car whereupon the car is then moved into the oven for the purpose of drying the mold. When moving the car into the oven the mold is subjected 20 to a heat of great intensity and consequently the car wheels. In using the cars in the ordinary construction, in which the wheels are journaled upon the axles, the great heat to which the axles are subjected causes an 25 expansion of the frictional surfaces whereby the wheels are locked against rotation upon the axles. When attempting to remove the car and molds from the oven, it will be evident that in using cars of the ordinary construction it will be impossible 30 to remove the car as the wheels are locked upon the axle. It is obvious that the result is the ruination of the molds and the cars and the destruction of the bottom and 35 walls of the furnaces.

The chief characteristic of this invention is to overcome the above objection by constructing a car wheel which eliminates the use of axles and furthermore obviating the 40 liability of the wheels expanding to prevent the rotation thereof when subjected to the heat in the oven.

Another characteristic of this invention is to provide a device of the above described character in which the wheels are 45 provided with flanges that are engageable with the rails upon which the wheels are mounted to prevent the accidental derailing of the car.

50 Another characteristic of this invention is to provide a car wheel comprising a casting and a ball loosely mounted within the casting and engageable with the rails to movably support the car upon the rail, the casting being formed in sections to permit the

interchanging of the ball in the event that it becomes worn and distorted.

A further characteristic of this invention resides in the provision of a device of the above described character which contains 60 the desirable features of simplicity, durability and efficiency and furthermore a device which may be manufactured at a nominal cost.

Other characteristics of the invention will 65 appear as the specification is read in connection with the accompanying drawing, in which:—

Figure 1 is a side elevation of our improved form of wheels showing the same 70 applied to a car.

Fig. 2 is a bottom plan view of one of the wheels.

Fig. 3 is a transverse section taken on the line 3—3 of Fig. 1.

Fig. 4 is a longitudinal section of Fig. 1.

Fig. 5 is a longitudinal section of a modified form of wheel.

Fig. 6 is a further modified form.

Fig. 7 shows a section of the preferred 80 form of wheel.

Referring to the drawings in detail, our invention comprises a car generally indicated as at A which is formed of the upper rectangular frame 1 and the lower rectangular frame 2. The frames 1 and 2 are disposed in spaced relation to each other and are connected by the side and end rails 3 and 4, at their confronting faces. Within 85 this structure are longitudinally extending bars 5 preferably I-beams which are arranged at regular spaced intervals and have their opposite ends secured to the end rails, as is clearly shown in the drawings. Between the I-beams or bars 5 and side rails 90 are the reinforcing blocks 7, and between the bars are other blocks 8, all of which extend transversely of the car and are arranged at various intervals throughout the length of the structure.

95 It will be evident from the foregoing construction that we have provided a car body which is of strong and durable construction and which minimizes the liability of the collapsing of the car when subjected to the intense heat of the foundry furnaces. It is to be understood that when using this car in foundries the mold is adapted to be placed upon the upper side of the car, the particular arrangement of the blocks 8 and bars 5 100

105 110

preventing the sagging or bending of the bars and producing a car which is highly desirable for the purpose for which it is intended.

- 5 Secured to the under side of the lower frame 2 at the opposite ends thereof and extending transversely of the car body are the plates 9 which are provided with the openings 10, the openings being adapted to receive the chains (not shown) for securely holding the mold upon the car. Detachably secured to the under side of the plates 9 are our improved forms of wheels generally indicated as at B, the wheels being arranged 15 upon the plates 9 in pairs, the wheels of one pair being arranged in longitudinal alinement with the wheels of the remaining pair to form a substantial support for the car A. The wheels B each comprise two sections 11 and 12, the upper section 11 being of substantially rectangular formation and having the side walls thereof curved in the form of an arc to reinforce the construction thereof. Secured to the lower face of 20 the upper section 11 is a lower section 12 which is of substantially semi-circular formation the side walls thereof being rounded to form a continuation of the rounded sides of the upper section 11, thus producing 25 the curved sections which are strong and substantial. The curved or lower sides of the lower sections 12 are each provided with arcuate shaped grooves 13 which form the spaced flanges 14.
- 30 35 In the preferred embodiment of our invention as shown in Fig. 3 of the drawings, the lower section 12 is provided at its medial portion with a vertically extending cylindrical bore or opening 15, the lower end of 40 the opening being disposed within the grooves 13 and between the flanges 14. The upper end of the opening 15 has the walls thereof interiorly threaded to receive the plugs 16, the lower end of the plug being 45 curved in the form of an arc to provide a bearing 17. Mounted within the lower end of the opening 15 is a ball 18 which is formed of any suitable material such as metal or the like and which is of a diameter 50 slightly less than that of the opening 15 to permit free rotation of the same therein. The lower end of the opening is restricted by a flange 19 whereby a portion of the surface of the ball 18 will be disposed exteriorly of the section for contact with the rail as is clearly shown in the drawing. The bearing 17 is adapted to engage the ball 18 to prevent upward movement of the latter and at the same time to allow the ball 18 to 55 freely rotate within the opening 15. By threadedly mounting the plug 16 within the opening 15, the same may be adjusted vertically within the opening to allow for expansion and contraction of the ball 18 when 60 the car is within the oven of the furnace 65

whereby the accidental binding of the ball to prevent rotation thereof will be eliminated. It will be evident from the foregoing construction that when the wheels B are placed upon the tracks, the balls 18 will rotate over the surface of the rail to permit the moving of the car thereupon, while the flanges 14 will be disposed upon the opposite sides of the rail to prevent excessive lateral movement of the car and consequent 75 derailing of the same.

It will be thus seen that we eliminate the use of axles and the liability of the rotating element binding under the action of the intense heat when the car is in the oven of 80 the furnace, and that the liability of the car becoming stalled within the open is eliminated.

To originally hold the wheels within vertical position the plates 9 are provided with 85 brace bars 20 which extend longitudinally of the plates and have their confronting ends engaging the opposite sides of the wheels as is clearly shown in the drawings. The brace bars engage the wheels in such a 90 manner as to permit the ready removal of the lower sections 12, it being understood that the lower sections are detachably connected with the upper sections 11 by means of the rods 21 and the bolts 22.

In Fig. 5 we have shown a modified form of wheel in which the lower section 12 is provided with a similar opening 15 which has its lower end restricted by the flange 19, the pair of balls 23 being mounted within the opening and having their surfaces engaging each other. The lower ball is adapted to project into the groove 13 while the upper ball is confined within the opening by means of the plate 24, the latter being 100 formed with an opening 25 which is of a diameter less than the opening 15 whereby the upper ball will be locked in the opening 15 as will be understood.

In Fig. 6 we have shown a further modification in which a single ball is mounted within the opening 15, the opening 15 being of spherical formation to receive a relatively large ball 26 which has a portion thereof disposed within the groove 13. The 110 ball 26 is confined within the opening 15 by means of the plate 27 which is arranged upon the upper side of the section 12 and is provided at its medial portion with an opening 28 which is of a diameter less than that 115 of the opening 15 whereby the accidental removal of the ball will be prevented. It is to be understood that the plate 27 is removable to permit the removal of the ball, the opening 28 giving access to the opening 15 120 and at the same time reducing the amount of friction.

From the foregoing description taken in connection with the accompanying drawing, it will be evident that we have provided 125

an improved construction of car and wheels which is particularly useful in temperatures of great intensity and especially in foundries for transporting molds to and from the oven of the furnaces. The proper operation of the car is insured in that the car body which is of a strong and substantial construction to prevent the accidental collapsing of the same and furthermore the wheels are so constructed as to eliminate the liability of binding when the frictional surfaces are expanded.

It is thought from the foregoing taken in conjunction with the accompanying drawings, that the construction and operation of our device will be apparent to those skilled in the art, and that minor changes in the size, shape, proportion and minor details of construction may be made without departing from the spirit and scope of the appended claims.

What we claim is:

1. A car wheel comprising a member having a curved lower face and provided with an upright bore opening through the top of the member and through its lower face, means for removably closing the upper end of said bore, flanges on said lower face restricting the lower end of the bore, and a ball in such bore resting upon said flanges and projected below said lower face by contact with said means.

2. A car wheel comprising a member having a curved and channeled lower face and provided with an upright bore opening through the top of the member and through its lower face into said channel, a bearing for removably closing the upper end of said bore, flanges on said lower face and within its channel restricting the lower end of the bore, and a ball in such bore resting upon said flanges and projected below said lower face by contact with said bearing.

3. A car wheel comprising a member having its lower face curved and its body provided with an upright cylindrical bore opening through its top and through said face,

the bore being threaded at its upper end and restricted at its lower end, a plug screwed into such threaded end with its lower extremity forming a bearing, and a ball within such bore resting on the restricted end thereof and projected beyond the curved face of said member by contact with said bearing.

4. A car wheel comprising a member having a curved base portion, and an opening formed therein, the lower end of the opening being restricted, spaced flanges formed on the curved portion and disposed upon the opposite sides of said opening, a ball mounted within said opening and having a portion thereof exposed between said flanges and a bearing removably mounted within said opening and engageable with said ball.

5. A car wheel comprising a base and a tread section, said sections being detachably connected to each other, the tread section being of arcuate shaped formation and having spaced arcuate shaped flanges formed on the tread section, said tread section having an opening formed therein, the lower end of which is restricted and disposed between said flanges, a ball journaled within the opening having a portion disposed between said flanges, a bearing mounted within said opening, and a plate interposed between said sections and spanning said opening to retain the bearing within the opening.

6. A car wheel comprising a base section and a tread section, said sections being detachably connected to each other, the tread sections being of arcuate shaped formation and provided with a vertical opening, arcuate shaped flanges disposed upon opposite sides of the opening, the lower end of the opening being restricted, a ball journaled within the opening and having a portion thereof exposed between said flanges, and a bearing threadedly mounted within said opening and engageable with said ball.

In testimony whereof we affix our signatures.
